UNITED STATES PATENT OFFICE

170,026

CHILD'S RIDING TOY OR SIMILAR ARTICLE

Leslie C. Peltier, Delphos, Ohio, assignor to
The Delphos Bending Company

Application February 9, 1953, Serial No. 23,519

Term of patent 14 years

(Cl. D34—15)

To all whom it may concern:

Be it known that I, Leslie C. Peltier, a citizen of the United States, residing at Delphos, in the county of Allen and State of Ohio, have invented a new, original, and ornamental Design for a Child's Riding Toy or Similar Article, of which the following is a specification, reference being had to the accompanying drawing, forming a part thereof.

Fig. 1 is a perspective view of a child's riding toy or similar article, showing my new design;

Fig. 2 is a top plan view thereof; and

Fig. 3 is a front elevational view thereof.

I claim:

The ornamental design for a child's riding toy or similar article, substantially as shown.

LESLIE C. PELTIER.
